DESIGN FOR A COMBINED WRINGER AND
CASING FOR A WASHING MACHINE

Henry Dreyfuss, New York, N. Y., assignor to
Nineteen Hundred Corporation, Binghamton,
N. Y., a corporation of New York

Application July 11, 1933. Serial No. 48,684

Term of patent 14 years

To all whom it may concern:

Be it known that I, HENRY DREYFUSS, a citizen of the United States, residing at New York, in the county of New York and State of New York, have invented a new, original, and ornamental Design for a Combined Wringer and Casing for a Washing Machine, of which the following is a specification, reference being had to the accompanying drawing, forming a part hereof, in which:

Fig. 1 is a perspective view of a combined wringer and casing for a washing machine showing my new design; and

Fig. 2 is a plan view of the same.

I claim:

The ornamental design for a combined wringer and casing for a washing machine, as shown.

HENRY DREYFUSS.
